[57] CLAIM

The ornamental design for a female mannequin or the like, as shown and described.

DESCRIPTION

FIG. 1 is a front elevational view of a female mannequin or the like showing my new design;

FIG. 2 is a top plan view thereof;

FIG. 3 is a left side elevational view thereof, the opposite side being substantially a mirror image of that shown;

FIG. 4 is a rear elevational view thereof; and

FIG. 5 is a top plan view thereof.

FIG. 3
